UNITED STATES PATENT OFFICE.

WILLIAM M. STEVENSON, OF OSHKOSH, WISCONSIN, ASSIGNOR TO WAITE GRASS CARPET COMPANY, OF OSHKOSH, WISCONSIN, A CORPORATION OF WISCONSIN.

RUG.

Application filed September 15, 1924. Serial No. 737,666.

To all whom it may concern:

Be it known that I, WILLIAM M. STEVENSON, a citizen of the United States, residing at Oshkosh, in the county of Winnebago 5 and State of Wisconsin, have invented certain new and useful Improvements in Rugs, of which the following is a specification.

This invention is directed to a woven rug having a warp, preferably composed of 10 twisted paper twine, commonly known as fiber, and a weft composed of grass twine. The combination of these two materials in a woven rug displays a number of special features of advantage which cannot be attained in the use of the materials separately. 15 The grass twine, being relatively stiff and bulky affords the necessary body to the rug, and also provides an intermediate cushion for the warp strands, which, being made of 20 tightly twisted paper, constitute the wearing surface of the rug and affords high resistance to abrasive action. At the same time the presence of the grass weft prevents the packing down of the paper warp, 25 which is an objectionable characteristic of fiber rugs composed entirely of paper twine.

In like manner, the bulky weft serves to afford the necessary interstices in the rug fabric to permit the rug to quickly dry out 30 in case it becomes wet, which is a feature of importance in rugs including paper twine as a constituent.

The invention, in its more limited aspects, is directed to the manner in which the paper 35 warp strands are interlaced so as to afford lines of diagonally extending closely laid ribs or elevations which completely protect the more friable weft from abrasive action.

Further objects and features of the present 40 invention will appear from a detailed description thereof.

In the drawings:

Figure 1 is a plan view of a section of rug embodying the features of the present 45 invention;

Fig. 2 is an enlarged cross sectional view cutting across the grass weft strands;

Fig. 3 is an enlarged cross-sectional view at right angles to that of Fig. 2, cutting 50 across the warp strands;

Fig. 4 is a length of one of the weft strands; and

Fig. 5 is a length of one of the warp strands.

55 The rug consists of a plurality of weft

strands A, each of which is composed of a series of straight laid overlapping wisps of stiff flexible wire grass B which are bundled together and secured by means of a wrapping thread C, as is common in the 60 forming of grass twine.

The weft strands A are laid in parallel relation and spaced apart sufficiently to permit the interweaving of the warp 65 strands D. The warp strands, as shown, in Fig. 5, are formed of lengths of tough fibrous paper E twisted together to form a somewhat bulky twine having a diameter, as shown, of about one-third of that of the weft strands. The character of the paper 70 twine, ordinarily used in rug construction, at the present time, is such as to afford a very considerable tensile strength and a surface which is highly resistant to abrasive action. 75

The warp strands, in the rug illustrated, are interwoven with the weft strands in the following manner: Each warp strand is interlaced alternatively over and under two of the weft strands, but in such relation as to afford a series of diagonally extending ribs or elevations F, each rib or elevation comprising the closely adjacent portions of succeeding warp strands, which, lying in contact with one another, afford an unbroken rib of considerable thickness or bulk which cushions against the interposed weft strands. 80

As indicated in Fig. 1, and reading from the left lower side, the first warp strand 90 will underlie the first pair of weft strands and overlie the second pair and so on. The second warp strand will overlie the first single weft strand and then begin to underlie and overlie the warp in pairs, which break with the pairs about which the first warp strands are interlaced. The third warp strand will overlie the first pair of weft strands and underlie the second pair, thus breaking joints evenly with the first warp strand, and the fourth warp strand 100 will underlie the first individual weft strand and then break joints evenly by pairs of weft strands with the second warp strand. Since the adjacent warp strands recurrently lie in close lateral contact with one another, any lateral shifting of the warp strands will be impossible, and since the first and third and second and fourth warp strands are passed in opposite directions through the same space 105 110

between the weft strands, the latter will be tightly interlocked and held against outward protrusion or bulging, so that no portion of the grass surface will be exposed to

5 abrasion, although sections thereof will be visible which affords a pleasing appearance to the rug, and at the same time provides gaps or spaces between the upstanding warp ribs, so that moisture may easily evaporate
10 and prevent a matting down of the paper surface.

By combining a grass weft with a fibrous paper twine warp the rug fabric, as a whole, is stiffened in both ways. That is, the stiffness 15 is divided equally between the paper warp and the grass weft. This avoids a tendency of the fabric to buckle and creep which is common in ordinary grass rugs which lack a warp having any material degree of stiffening action.

The present rug, by reason of an equal balance of stiffness, will lie perfectly flat and cannot buckle. Not only is there a balance as to stiffness, but there is substantial equality 25 in the weight of materials and a balance on the wearing qualities. Rugs made entirely of fiber lack this balance and have a tendency to buckle, unless a heavy sizing is applied. In the present invention, by reason of the equal division of stiffness and weight, the fabric cannot kick up either at the sides or ends which is not true where there is a marked disparity in weight between the materials used for the warp and 30 the weft.

In the rug of the present invention the grass wisps employed in the weft are sufficiently stiff to afford the necessary stiffening quality, but these fibers being laid in an un-twisted twine at the same time afford a highly desirable cushion filler for the warp strands to enable the desired close packing thereof.

The manner of interlacing the warp with the grass weft is such that it not only firmly binds the fabric together, but also forms a protective wearing surface and prevents dis-integration of the grass weft which is a common 45 objection to grass rugs of the ordinary character. In addition to the above, the paper twine, being of a fibrous character, readily absorbs color, so that a stencil design can be applied to the fabric, in which case, the color, adhering to the exposed portions of the grass surface will not be subjected to wear which is important, since the hard enamel like surface of the wire grass wisps will not absorb color and requires protection against abrasion in order to prevent 50 a rubbing off of the color. Furthermore, by use of a paper twine warp, multiple color effects can be introduced during the weaving of a rug, since the strands of paper twine can be readily dyed to any color or combination of colors, and since the warp affords

at least half of the exposed surface, the resulting color effect will partake in very large measure of the colors imparted to the warp strands.

The rug as a whole is one which obviates practically all of the objections which have heretofore attended the use of an all grass rug on the one hand, or an all paper twine rug, commonly known as a fiber rug, on the other, and at the same time combines the desirable qualities of these materials, both of which are relatively inexpensive as compared with yarns or fabrics commonly employed in the weaving of rugs. The resulting rug is one which, by reason of its comparatively open character, will not readily retain dirt, sand or grit, which makes it peculiarly adapted for porch use, and at the same time the comparatively soft texture of the wearing surface, as well as its pleasing appearance, adapts it for indoor use in cases where a grass rug would not be deemed suitable.

I claim:

1. In a rug, the combination of a plurality of relatively bulky weft strands of grass twine extending in parallel relation to one another, and a warp composed of warp strands of fibrous material interlaced through the weft strands and laid in close laterally adjacent relation to one another and standing away from the weft strands to prevent exposure of the grass twine to abrasive action, substantially as described.

2. In a rug, the combination of a plurality of relatively bulky weft strands of grass twine extending in parallel relation to one another, and a warp composed of warp strands of fibrous material interlaced through the weft strands and laid in close laterally adjacent relation to one another and standing away from the weft strands to prevent exposure of the grass twine to abrasive action, each warp strand passing alternately under and over a pair of weft strands, and laterally adjacent warp strands dividing the pairs of weft strands, substantially as described.

3. In a rug, the combination of a plurality of relatively bulky weft strands of grass twine extending in parallel relation to one another, and a warp composed of warp strands of fibrous material interlaced through the weft strands and laid in close laterally adjacent relation to one another and standing away from the weft strands to prevent exposure of the grass twine to abrasive action, each warp strand passing under and over pairs of weft strands, the first and third warp strands interlacing with one pair of weft strands, the second and fourth warp strands dividing the first mentioned pair of weft strands and interlacing with another pair of weft strands to afford diagonally outstanding ribs composed of ex- 130

posed sections of adjacent warp strands, substantially as described.

4. In a rug, the combination of parallel relatively bulky weft strands composed of 5 bundles of overlapping wisps of grass in straight laid relation, and a warp composed of twisted paper twine, the warp strands being interlaced between the weft strands in close lateral relation to one another to afford 10 an upstanding wearing surface above the plane of the grass surface to prevent abrasive action thereon, substantially as described.
5. In a rug, the combination of parallel 15 relatively bulky weft strands composed of bundles of overlapping wisps of grass in straight laid relation, and a warp composed of twisted paper twine, the warp strands being interlaced between the weft strands 20 in close lateral relation to one another to afford an upstanding wearing surface above the plane of the grass surface to prevent abrasive action thereon, each warp strand passing alternately under and over a pair of

weft strands, and laterally adjacent warp 25 strands dividing the pairs of weft strands, substantially as described.

6. In a rug, the combination of parallel relatively bulky weft strands composed of 30 bundles of overlapping wisps of grass in straight laid relation, and a warp composed of twisted paper twine, the warp strands being interlaced between the weft strands in close lateral relation to one another to afford 35 an upstanding wearing surface above the plane of the grass surface to prevent abrasive action thereon, each warp strand passing under and over pairs of weft strands, the first and third warp strands interlacing with one pair of weft strands, the second 40 and fourth warp strands dividing the first mentioned pair of weft strands and interlacing with another pair of weft strands to afford diagonally outstanding ribs composed of exposed sections of adjacent warp strands, 45 substantially as described.

WILLIAM M. STEVENSON.
